UNITED STATES PATENT OFFICE

2,444,188

AUTOMATIC ELECTRIC TOOLHOLDING SWITCH

Edwin H. L. Englund, Muskegon Heights, Mich.

Application November 6, 1944, Serial No. 562,185

1 Claim. (Cl. 200—85)

1

This invention relates to automatic electric switch construction, and aims to provide a novel form of switch for use in connection with motor-driven tools such as forming a part of routing machines, the switch embodying a support for the tool which actuates the switch to break the circuit to the motor providing the power for operating the tool, when the tool has been placed on the support, the weight of the tool operating the switch as described.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawings

Figure 1 is an elevational view of a routing machine, equipped with an automatic switch constructed in accordance with the invention.

Figure 2 is a side elevational view thereof.

Figure 3 is a modified form of switch designed primarily for use with the rail-type of router machines.

Figure 4 is an enlarged longitudinal sectional view through the switch and switch housing.

Figure 5 is a similar longitudinal sectional view illustrating the switch in its open position.

Figure 6 is a sectional view taken on line 6—6 of Fig. 4.

Figure 7 is a sectional view taken on line 7—7 of Fig. 4.

Figure 8 is an enlarged fragmental sectional view through the switch housing, illustrating the arm which is connected with the switch for manually operating the switch.

Referring to the drawings in detail, the machine embodies a stand 5 on which the motor indicated at 6 is mounted, the motor being provided with the usual motor shaft on which the pulleys 7 and 8 are mounted, the shaft and pulleys transmitting motion to the flexible shaft 9 of the machine, through the belt 10 and pulleys 11 and 12.

Rising from the motor casing, is a post 13 which is hollow, to accommodate the wires 14, providing the circuit between a source of electricity supply, and the motor.

Mounted on the upper end of the tubular post 13, is the switch housing 15 which is formed with an opening in the upper end thereof, to accommodate the switch spindle 16. This switch spindle

2

16 operates through the tubular bearing 17 which is constructed of suitable insulating material. The bearing 17 is formed with an annular flange near its upper end, against which the contact ring 18 rests to move with the tubular bearing 17. Secured to the switch spindle 16 is a tubular bearing 19 against which the lower end of the tubular bearing 17 rests. A coiled spring indicated at 20 has its upper end resting against the tubular bearing 19, the lower end thereof resting on the bracket 21 which is secured to the inner surface of the switch housing 15, the bracket having an opening through which the spindle 16 moves. The head 22 of the spindle 16 is adapted to move into engagement with the upper end of the bracket 21, as shown by Fig. 4 of the drawings, limiting the upward movement of the spindle 16 when the tool has been removed from its supporting hook.

20 In order that the switch may be manually operated, an arm 23 is provided, which arm is secured to the bearing ring 19 and extends through a slot in the wall of the housing 15, there being provided notches to receive the arm 23, so that the arm and spindle may be secured in various positions of adjustment. The reference character 24 indicates a knob secured to the outer end of the arm 23 to facilitate the moving of the arm and spindle.

25 Mounted within the switch housing, are contact bars 25, which have their upper ends extended inwardly, providing contact members 26 adapted to be engaged by the contact ring 18, to complete the circuit through the contact members 25 to the wires 14, which are shown as connected with the terminals 27 at the lower ends of the contact bars.

30 The reference character 28 designates the support or hook for receiving the tool that receives its motion through the flexible shaft 9, and this support or hook comprises a body portion which is secured to the machine at the upper end thereof. The support or hook 28 is formed with an opening through which the rod 29 extends, the rod being formed with a plunger 30 at its lower end which is connected to the upper end of the spindle 16, as clearly shown by the drawings.

35 On the upper end of the rod 29 is a head 31 that normally extends above the surface of the support or hook 28 so that when the tool is positioned thereon, the tool, which in the present showing, is indicated by the reference character A, contacts the head 31 and moves the head and rod 29 downwardly, to the position as shown by Fig. 5 of the drawings, breaking the circuit be-

tween the bars 25 and consequently cutting off the current to the motor.

When the tool is removed for use, the coiled spring 20 will of course expand, moving the member 17 and contact ring 18 to the positions shown by Fig. 4 of the drawings, completing the circuit.

Due to this construction, it will be obvious that if the tool is returned to its support or hook, after use, the motor will be immediately cut off, and electric power, as well as wear and tear on the movable parts of the machine, will be reduced to a minimum.

What is claimed is:

A switch of the class described, comprising an elongated body portion, spaced elongated contact members mounted within the body portion, wires extending into the body portion and being connected with the lower ends of the elongated contact members, said wires being in circuit with a source of electric supply, providing an electric circuit to the contact members, the upper ends of the contact members extending at right angles providing contact points, a spindle operating within the body portion and being movable between the contact points, a tubular insulating member on the spindle insulating the contact points from each other, a contact ring carried by the insulating material and adapted to move into engagement with the contact points, completing

5 an electric circuit therethrough, said contact points providing a stop for the spindle and contact ring restricting upward movement of the spindle and contact ring, means for normally urging the spindle and contact ring towards the contact points, said contact ring and spindle adapted to move away from the contact points under weight directed to the upper end of the spindle, and manually operated means for moving the spindle and contact ring to break the circuit to the contact members, holding the circuit open.
